(57) **CLAIM**

The ornamental design for an owl contact lens case, as shown and described.

DESCRIPTION

FIG. 1 is a top plan view of an owl contact lens case of my design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a perspective view thereof; and,

FIG. 8 is a perspective view thereof with the lens covers removed.

The broken lines in the FIG. 8 marking the left and right lens reservoirs are for illustration purposes only and form no part of the claimed design.
